(57) **CLAIM**

The ornamental design for a trampoline as shown and described.

DESCRIPTION

FIG. 1 is a top perspective view of a trampoline, showing my new design;

FIG. 2 is a bottom perspective view thereof;

FIG. 3 is a front elevational view thereof, the rear elevational view, the left side view and the right side view are identical;

FIG. 4 is a top plan view thereof;

FIG. 5 is a bottom plan view thereof;

FIG. 6 is a partial enlarged view of FIG. 2; and,

FIG. 7 is a partial enlarged view of FIG. 5.

The dash-dot-dash lines are for annotating enlarged views, which form no part of the claimed design.

1 Claim, 6 Drawing Sheets(56)
